UNITED STATES PATENT OFFICE.

JAMES T. GRIFFIN, OF OAK PARK, CARL A. NELSON, OF CHICAGO, AND MELVIN H. CAMPBELL, OF CICERO, ILLINOIS, ASSIGNEES TO WESTERN ELECTRIC COMPANY, INCORPORATED, OF NEW YORK, N. Y., A CORPORATION OF NEW YORK.

SOLDERING-MACHINE.

1,379,684.

Specification of Letters Patent. Patented May 31, 1921.

Application filed October 18, 1918. Serial No. 258,724.

To all whom it may concern:

Be it known that we, JAMES T. GRIFFIN, residing at Oak Park, in the county of Cook and State of Illinois, CARL A. NELSON, residing at Chicago, in the county of Cook and State of Illinois, and MELVIN H. CAMPBELL, residing at Cicero, in the county of Cook and State of Illinois, citizens of the United States, have invented certain new and useful 10 Improvements in Soldering-Machines, of which the following is a full, clear, concise, and exact description.

This invention relates to soldering machines, and more particularly to a machine 15 for soldering copper plated carbon disks of granular transmitters to their supports.

The object of this invention is to provide a machine by means of which the operation of securing a disk to its support may be 20 rapidly and efficiently performed with a minimum of manual operation.

In accordance with the general features of this invention, there is provided a machine comprising a movable work carrier having a 25 plurality of sets of work holding openings provided therein, each set being adapted to be moved in sequence from a loading position to an unloading position and operations performed intermediate these positions 30 which secure the disks and supports together. Preferably the work carrier comprises an intermittently rotatable member having a plurality of radially arranged sets of openings adapted to receive the parts to be operated upon. In one position of each of said openings the disks are automatically fed into the openings and this set of openings is then advanced into another position in which solder is automatically fed in the 35 proper amounts into the openings containing the disks. In subsequent movements of the carrier the set of openings containing the disk and solder receive the support, and this set is then advanced into a position 40 where it is operated upon by soldering irons. The auxiliary heating element positioned below the soldering irons and in contact with the part functions with the irons to quickly and thoroughly melt the solder. 45 Subsequent to the operation by the soldering irons the parts are brought successively into a position for operation of a centering tool, and into a final position from which they 50 are ejected from the carrier. Located di-

rectly below the centering position is a cooling chamber which insures a sufficient cooling of the parts before ejection from the carrier. The operation of the disk feeding mechanism, the solder supplying means, the soldering irons, the centering tools, and the ejectors are automatic and simultaneous and are controlled in the operation of rotating the work carrier.

In the drawings illustrating this invention:

Figure 1 is a plan view of a mechanism embodying the features of the invention;

Fig. 2 is a vertical cross-sectional view of parts illustrated in Fig. 1;

Fig. 3 is a horizontal sectional view taken 70 upon line 3-3 of Fig. 2 and illustrates the operating mechanism for driving the apparatus;

Fig. 4 is a view in side elevation with parts in section of the soldering supplying 75 mechanism;

Fig. 5 is a view in end elevation of the mechanism shown in Fig. 4;

Fig. 6 is a fragmentary detailed view of parts shown in Figs. 4 and 5;

Fig. 7 is a fragmentary plan view of the solder feeding mechanism;

Fig. 8 is a detailed cross-sectional view of the disk supplying mechanism;

Fig. 9 is a plan view of the parts shown 85 in Fig. 8;

Fig. 10 is a fragmentary detailed view of the disk supplying mechanism;

Fig. 11 is a plan view of a supporting plate for the soldering irons, centering 90 mechanism, and ejectors;

Fig. 15 is a detailed cross-sectional view illustrating the ejecting mechanism;

Fig. 16 is a fragmentary view of the base of the machine illustrating a cooling coil applied thereto;

Fig. 17 is an edge view of the parts shown in Fig. 16, and

Fig. 18 is a perspective view of the disk and the support to which it is to be secured.

In general, the apparatus of this invention

- comprises a hollow base 5 within which is supported a circular plate 6 upon which the disks bear while being operated upon and in being moved from one position to another.
- 5 The plate 6 is provided with circumferentially arranged grooves 7—7 centered with respect to the disks which reduce the friction on the disks when they are moved from one position to another. Mounted
- 10 below the base 5 is a motor 8 upon the shaft of which is mounted a worm 9, meshing with which is a worm gear 10 which is secured to a shaft 11. The worm gear 10 is mounted within a casing 12 suspended from the base
- 15 5. The shaft 11 extends upwardly through the bottom of the base 5 and has secured to it a mutilated gear 13 which meshes with a gear 14 secured to a sleeve 15 upon the upper end of which is mounted a rotatable
- 20 work carrier 16. Within the sleeve 15 is a shaft or stud 20 which is slidable therein and which is provided with a square end 21 which engages the housing 12 to hold it against rotation. This stud 20 is adapted
- 25 for a vertical reciprocating motion for operating the various parts of the mechanism, as will hereinafter appear.

Within the housing 12 is a cam 25 which coöperates with an arm 26 secured at one

30 end to the lower end of a stud 27 and having its other end rigidly secured to the stud 20. This cam 25 is secured to the shaft 11 to rotate therewith and causes the stud 20 to fall and rise with each complete revolution

35 of the shaft 11.

Securely fastened to the stud 20 above the carrier 16 are a pair of collars 30 and 31, the collar 30 carrying a plate 32, and the collar 31 carrying a plate 33. The upper

40 end of stud 27 after passing through a boss 28 on base 5 is secured to a boss 34 on the plate 32. These plates 32 and 33 form the movable supports for the soldering, centering, and ejecting mechanisms as will here-

45 inafter be set forth. Also carried by the stud 20 and located between the collars 30 and 31 are a second pair of collars 35 and 36 carrying projecting arms 38 and 39 respectively which coöperate with the disk

50 supplying mechanism and the solder supplying mechanisms respectively.

As shown in Fig. 1, the carrier 16 comprises a plurality of radially arranged arms 40, 41, 42, 43, 44, 45, 46, and 47, each being

55 provided with two rows of circular openings 48—48, each opening being provided with radially arranged fins 49—49, the upper ends of which are sloped outwardly to assist in receiving and centering the circular parts

60 to be operated upon. The arms 40, 41, 42, etc., are so spaced around the surface of the carrier 16 that they are moved one step equal to the distance between adjacent arms for each revolution of the shaft 11. Eight con-

secutive steps are made by each arm in a 66 complete cycle of operation; that is to say, between the point where the first disk loading operation occurs and the point where any particular arm is again in position for the disk loading operation.

The disk supplying apparatus comprises a plurality of tubular hoppers 50—50 each of which contains a column of disks 51—51, the lower disk of each column resting upon a plate 52 provided with openings 53—53 of sufficient size to permit the passage of the disks therethrough. The lower disk of each column which normally rests upon the plate 52 is located within an opening 54 in a slide plate 55 which is adapted in the operation of the mechanism to move the lower disk of each column into register with the openings 53—53 in the plate 52, thereby permitting them to drop through the openings 53—53 into the openings 48—48 in one of the arms of the carrier. The movement of the slide plate 55 is controlled through the agency of a lever arm 56, the lower end of which engages a slot in said slide plate, the upper end being pivoted on a stud 57 and secured to operate with a crank arm 58 which is controlled by the projecting arm 38 carried by the collar 35 on the sleeve or stud 20. As this sleeve or stud 20 is moved downwardly in response to the operation of the cam 25 the lever 56 will swing to the left, as viewed in Fig. 8, to move the disks 51 into the openings 53—53 of the plate 52. Upon its return or up movement the arm 38 will restore the slide plate 55 to its normal position, whereupon another set of disks will be fed into the opening 54—54 ready for a subsequent operation of the mechanism.

The collar 35 is provided with a pin 60 by means of which the arm 38 may be swung out of engagement with the crank arm 58 thereby displacing the automatic feeding of the disks into the work carrier in case it is so desired.

The solder is supplied to the disks in the openings 48—48 in the proper amounts through the agency of a feeding mechanism which comprises a pair of rollers 65, 66, between the adjacent surfaces of which strips of solder 67 are drawn. The free end of these solder strips extend through pilots 68—68 into position to be operated upon by knives 69—69. The feed roller 66 is provided with a knurled or roughened surface and is adapted to be rotated through the agency of a ratchet wheel 70 operated by a pawl 71 which is carried upon a pivoted arm 72, the outer end of which is bifurcated, and is engaged by the end of the arm 39 carried by the collar 36 on the stud 20. A link 73, one end of which is supported upon the arm 72, extends downwardly and engages,

5 by means of a stud 74 at its lower end, a pair of links 75 and 76 secured to longitudinally extending rods 77 and 78 to which are secured the knives 69-69. These knives 10 69-69 coöperate with a cutting block 69' to sever the ends of the strips of solder 67-67 which drop into the openings 48-48 upon the disks 51-51 therein.

10 In the operation of this mechanism the downward movement of the stud 20 causes a corresponding downward movement of the lever arm 72 which, through the agency of the link 73 and the links 75, 76, causes the knives 69-69 to move forward to sever the 15 projecting ends of the solder strips. Upon its return or upward movement the arm 72 through the agency of the pawl 71 rotates the ratchet 70 through the distance of one tooth or more, depending upon its adjustment, to feed the solder strips downwardly 20 again for a succeeding operation of the knives 69-69.

Soldering irons 80-80 are yieldingly supported between the plate 33 and an arm 81 25 on the plate 32. The yielding connection for each iron comprises a spring 82, one end of which is secured to a pivotal lever 83, the other end to an adjustable stud 84 which extends upwardly to the upper portion of a 30 casing 85 and has secured to it a wing nut 86 which bears against the upper portion of said casing 85. The lever 83 extends inwardly through the side wall of the casing 85 and has its inner end bifurcated to engage 35 a collar 87 on the soldering iron 80. Electrical connections are made to the soldering irons 80 within the casing 85 through the agency of flexible conductors and binding posts 88.

40 Due to the fact that the support to which the disk is to be soldered is slightly less in diameter than the disk, it is necessary to provide some sort of centering mechanism whereby the two parts may be centered with 45 respect to each other. As shown in Figs. 13 and 14, the centering mechanism for each device soldered comprises a pair of eccentrically adjustable sleeves 89 and 90 which are adjustably mounted in openings 91 in an 50 arm 93 of the plate 32. Extending through the inner sleeve 90 is a stud 94, the lower end of which is provided with an enlarged portion 95 having a centering opening 96 therein adapted to engage a stud 97 on a support 55 98 to which a disk 51 is soldered. A coil spring 99 surrounds the stud 94 with one end in engagement with the enlarged portion 95 thereon, the other end being in engagement with the lower portion of the sleeve 90. 60 This spring 99 permits the stud 94 to yield under pressure, thereby preventing injury to the disks 51 which are of comparatively fragile material.

After passing the centering mechanism

the parts previously operated upon are 65 brought into a position where they are adapted to be operated upon by plungers or studs 105-105 carried by an arm 106 of the plate 32. These studs 105-105 are directly above openings 107-107 in the plate 6 70 which are sufficiently large to permit the easy passage of the finished parts there-through.

An auxiliary heating element 110 is supplied beneath the carrier 16 and directly below the soldering irons 80-80. This heating element is used for the purpose of insuring a sufficient heat upon the disks to thoroughly melt the solder to cause the adhesion of the disk to its support. This auxiliary 80 heating element may be supplied with electrical energy through the agency of conductors 112-112.

The solder between the disk and support remains in a plastic condition after the section 85 of the carrier 16 carrying these parts has left the soldering position and until the centering mechanism has been brought into operation. In order, however, to insure that the parts will be sufficiently cooled before 90 ejection from the carrier a cooling pipe 115, which may be supplied either with cold air or water, is run through a section of the plate 6 directly beneath the position of the centering devices. 95

The operation of the mechanism of this invention briefly is as follows:

The operator starts the machine by starting the operation of the motor 8. As this motor operates, it turns the shaft 11 which, 100 through the agency of the mutilated gear 13 and the gear 14, starts the carrier 16 to rotating intermittently. The rotation of the shaft 11 also rotates the cam 25 which as it rotates lowers and raises the stud 20 which 105 lowers and raises the plates 32 and 33 and the arms 38 and 39. As hereinbefore pointed out, the raising and lowering of the arm 38 causes disks to be fed into openings 48-48 of whichever arm of the work carrier 110 16 is then in position under the tubes 50-50. The reciprocating movement of the arm 39 cuts and feeds the solder, the severed portions of which are caused to drop upon disks in the openings 48-48 of the arm of the rotatable carrier 16, which is then in position under the solder feeding mechanism. Between the time that any particular arm passes between the solder feeding mechanism and the soldering irons the operator drops 115 120 into the openings of the two exposed arms of the carrier 16 the metal supports 98-98 to which the disks 51-51 are to be secured. Each down and up movement also causes a corresponding movement of the soldering 125 irons, the centering studs, and the ejecting plungers so that at each complete movement of this stud 20 one set of articles is being

soldered, another is being centered, and a third is being ejected from the supporting openings of the carrier 16.

The advantages of the mechanism of this invention are that the operation can be made practically continuous, and the only manual operation required is the supplying of the metal parts 98—98 to which the carbon disks 51—51 are secured.

10 The capacity of the machine may be increased by lengthening the arms 40, 41, 42, etc., and supplying them with a greater number of the openings 48—48.

What is claimed is:

15 1. In a machine for soldering disks to supports, an intermittently rotatable work carrier having a plurality of sets of work holding openings therein each adapted in the rotative movement of said carrier to be moved into consecutive positions to complete a cycle of operations, a plate associated with said carrier for supporting the disks, means for supplying disks to each set of openings in one position of said carrier, means for supplying solder to said openings in another position thereof, heat applying means adapted to operate upon the supports in a following position of said carrier to melt the solder, means for centering the supports on the disks and ejecting the soldered article from the carrier in the positions of the carrier succeeding the soldering position.

20 2. In a machine for soldering disks to supports, an intermittently rotatable work carrier having a plurality of sets of work holding openings, a plate associated with said carrier for supporting the disks, automatically operated means for supplying disks to each set of openings in one position of said carrier, means for automatically supplying solder to each of said sets of openings in a succeeding movement of said carrier, soldering irons automatically operated to fuse the solder between said disks and said supports, means for centering said supports with respect to said disks while

the solder is in a plastic condition, and means for ejecting said parts from the carrier.

50

25 3. In a machine for soldering disks to supports, a rotatable work carrier having a plurality of sets of openings therein, each set being adapted to receive parts to be soldered, a plate associated with said carrier for supporting the disks, soldering irons located above said carrier and beneath which each set of openings is successively moved, and a heating element located below said carrier in position to coöperate with said 55 soldering irons.

4. In a machine for soldering disks to supports, a rotatable work carrier having a plurality of sets of openings therein, each set of said openings being supplied with parts to be soldered, a plate associated with said carrier for supporting the disks, movable soldering irons located above said carrier in position to coöperate with each set of openings in successive positions of said 60 carrier, centering mechanism located above said carrier and adapted to engage the soldered parts after they have left the soldering irons, and cooling means located beneath said carrier adjacent said centering 70 mechanism.

5. In a machine for soldering disks to supports, the combination with a work carrier, means for positioning solder on the work, and means for applying heat to unite 80 the parts, of a pair of eccentrically adjustable sleeves, a stud yieldingly mounted from said sleeves for vertical movement and adapted to be moved in a horizontal plane 85 by the adjustment of said sleeves, and means for operating said sleeves and stud to center the support on the disk.

In witness whereof, we hereunto subscribe our names this 1st day of October, A. D. 1918.

JAMES T. GRIFFIN.
CARL A. NELSON.
MELVIN H. CAMPBELL.
